CHARLES S. BARBOUR, JR., OF MERIDEN, CONNECTICUT.

BUTTON-FORM.

1,169,912.

Specification of Letters Patent. Patented Feb. 1, 1916.

Application filed May 20, 1915. Serial No. 29,339.

To all whom it may concern:

Be it known that I, CHARLES S. BARBOUR, Jr., a citizen of the United States, residing at Meriden, county of New Haven, State of Connecticut, have invented an Improvement in Button-Forms, (Case A,) of which the following is a specification.

This invention relates to button forms adapted to be covered with cloth and has for its object to provide a button form of this character adapted for general use and especially adapted for use by cloak-makers, tailors and dress-makers in the class of work requiring that the buttons match the garment or requiring buttons covered with a special fabric as distinguished from stock buttons, and especially to provide a button form of this character which shall be inexpensive to produce, easy to cover and to assemble and adapted to be easily and quickly re-covered with the same or another fabric and to be used for an unlimited number of times.

With these and other objects in view, I have devised the novel button form which I will now describe, referring to the accompanying drawing forming a portion of this specification and using reference characters to indicate the several parts:—

Figure 1 is a section of the front plate of my novel button form with the cover secured in place thereon; Fig. 2 a view as seen from the right in Fig. 1; Fig. 3 an elevation of the front plate detached; Fig. 4 an elevation of the clamping plate detached; Fig. 5 a section of an assembled button; Fig. 6 a section of the clamping plate on the line 6—6 in Fig. 4; Fig. 7 an elevation on a reduced scale of a button illustrating a use of my novel button form where two color buttons are required; Fig. 8 a section of the ring, detached, which is used in connection with my novel button form in the type of button illustrated in Fig. 7, and Fig. 9 is a section of a completed button corresponding with Fig. 7.

My novel button form comprises a front plate 10, a clamping plate 11 and a shank 12 having an eye 13. The front and clamping plates may be made of metal, celluloid, vulcanized fiber, or any suitable material. The front plate is shown as concavo-convex in form and is provided in its face with a central depression 14 and a slot 15 across the depression. The clamping plate is preferably dished slightly and is provided in its

outer face with a central depression 16, with a slot 17 across the depression and a groove 18 crossing the slot. In addition to the eye, the shank is provided at its opposite end with a head 19 which is received in the depression 14 in the front plate.

20 denotes a cover which is a disk of fabric enough larger than the front plate to permit the edge of the cover to be folded over the edge of the front plate and secured by stitching, as indicated by 21, in Fig. 2.

In assembling a button, the shank is first placed in position as in Fig. 1, the eye being passed through the slot and the head resting in the depression, then the cover is placed thereon, then the clamping plate is placed in position, as in Fig. 5, the eye being passed through slot 17 therein and then the shank is given a partial turn to cause the inner end of the eye to drop into groove 18 and lock the shank against rotation, there being sufficient spring or yield to the cover, clamping plate and eye to permit the shank to be turned by the application of a little power and to then retain the eye locked in the groove. When it is required to remove the cover the shank is given a partial rotation to place the eye in alinement with the slot in the clamping plate, when the clamping plate 25 may be readily removed and the cover released.

The form illustrated in Figs. 7, 8 and 9 differs in the addition of a ring 22 of greater diameter than the front plate, which may be covered by a fabric of contrasting color or an entirely different style of fabric. The ring is given a suitable ornamental configuration to correspond with the front plate and is provided in its face with a depressed flange 23 against which the edge of the covered front plate rests. The ring is covered with cloth in the same manner as the front plate, the cover of course extending over the opening in the ring. The clamping plate in this form does not engage the front plate as before but is of greater diameter and engages the back of the covered ring, as clearly shown in Fig. 9, in which the cover of the ring is indicated by 24. In assembling, the head of the shank is placed in the depression in the front plate as before, covers are placed over the front plate and the ring, the edge of the covered front plate is placed over the flange of the ring, the clamping plate is 30 placed in engagement with the back of the cover of the ring, the eye is passed through

the ring cover and through the slot in the clamping plate and then the shank is given a partial turn to cause the inner end of the eye to drop into the groove and lock the shank against rotation, as before. The disassembling for the purpose of recovering either front plate or ring is the same as before.

Having thus described my invention, I 10 claim:—

1. A button form comprising a front plate having a central depression and a slot crossing the depression, a shank having a head adapted to engage the depression and an eye 15 adapted to be passed through the slot, and a clamping plate having a central depression and a slot crossing the depression, through which the eye may be passed, the parts being locked in place by giving the shank a partial 20 turn.

2. A button form comprising a front plate having a central slot, a shank having a head adapted to engage the face of the front plate and an eye adapted to be passed through the 25 slot, and a clamping plate having a central slot through which the eye may be passed, the parts being locked in place by giving the shank a partial turn.

3. A button form comprising a front plate 30 having a central depression and a slot crossing the depression, a shank having a head adapted to engage the depression and an eye adapted to be passed through the slot, and a clamping plate having a central depression, 35 a slot crossing the depression through which the eye may be passed and a groove adapted

to be engaged by the inner end of the eye to lock the parts in place.

4. In combination, a front plate having a central slot, a shank having a head adapted to engage the face of the front plate and an eye adapted to be passed through the slot, 40 a cloth cover placed over the front plate and secured at the back, and a clamping plate having a central slot through which the eye may be passed, the parts being locked in place by giving the shank a partial turn. 45

5. In combination, a front plate having a central slot, a shank having a head adapted to engage the face of the front plate and an eye adapted to be passed through the slot, 50 a cloth cover placed over the front plate and secured at the back, a ring of greater diameter than the front plate through which the shank is passed, a cloth cover placed over the ring and secured at the back, and a clamping plate having a central slot through which the eye may be passed, the parts being locked in place by giving the shank a partial turn. 55

6. A button form comprising a front plate having a central slot, a shank having a head adapted to engage the face of the front plate and an eye adapted to be passed through the slot, a ring of greater diameter than the front plate through which the shank is 60 passed, and a clamping plate having a central slot through which the eye may be passed, the parts being locked in place by giving the shank a partial turn.

In testimony whereof I affix my signature. 70

CHARLES S. BARBOUR, JR.
